UNITED STATES PATENT OFFICE.

JOSEPH U. GEROW, OF BROOKLYN, NEW YORK.

DESIGN FOR PEN AND PENCIL CASES.

Specification forming part of Design No. 7,747, dated September 8, 1874; application filed July 25, 1874.
[Term of Patent 7 years.]

To all whom it may concern:

Be it known that I, JOSEPH U. GEROW, of Brooklyn, Kings county, New York, have invented or produced a Design for a Pen and Pencil Case, of which the following is a description, and the design is shown in the accompanying drawing.

The general design of the ornamentation of the metallic case is in imitation of the strands of a rope or cable. There are narrow grooves running longitudinally of the case, and preferably inclined slightly to the right, and there are spiral corrugations illustrative of the numerous strands of a cable, inclined at an angle to the left, like a many-threaded screw. The design for the exterior metal tube of a pen or pencil case is highly ornamental, and it is represented in the drawing.

A case for a pen or pencil has been made with inclined smooth corrugations, in imitation of a many-threaded screw. My design is in imitation of a rope or wire cable, and shows the imitation cords as well as strands.

I claim as my invention—

The ornamental design for the metallic pen or pencil case tube representing a rope or wire cable, as described, and as shown in the drawing.

Signed by me this 22d day of July, A. D. 1874.

JOSEPH U. GEROW.
